UNITED STATES PATENT OFFICE.

AUGUST F. LIPPERT, OF JAMESTOWN, NORTH DAKOTA.

ATTACHMENT FOR DOUBLE-DISK DRILLS.

1,183,088.

Specification of Letters Patent.

Patented May 16, 1916.

Application filed November 3, 1915. Serial No. 59,441.

To all whom it may concern:

Be it known that I, AUGUST F. LIPPERT, a citizen of the United States, residing at Jamestown, in the county of Stutsman,

5 State of North Dakota, have invented certain new and useful Improvements in Attachments for Double-Disk Grain-Drills; and I do hereby declare the following to be a full, clear, and exact description of the 10 invention, such as will enable others skilled in the art to which it appertains to make and use the same.

The present invention is directed to improvements in attachments for double disk 15 grain drills, and has for its object to provide an attachment of this nature which can be conveniently attached to the drill frame and will act to hold the disks in proper converging relation.

20 A further object of the invention is to provide an attachment of this nature which can be applied to any well known type of machine and provided with adjustably mounted rollers, whereby the disks can be 25 properly adjusted so that their forward peripheries will be held in such position as to prevent the disks from leaving a ridge between them as the drill is in operation.

With these and other objects in view, this 30 invention resides in the novel features of construction, formation, combination and arrangement of parts to be hereinafter more fully described, claimed and illustrated in the accompanying drawings, in which—

35 Figure 1 is a front elevation of the attachment showing the same in position on the beam of the drill frame. Fig. 2 is a side elevation of the same. Fig. 3 is a rear view of the attachment. Fig. 4 is a sectional view on line 4—4 of Fig. 3.

The attachment comprises a vertically arranged bar 1 which has a longitudinal slot 2 formed in its upper portion, said slot being engaged by the clamping bolts 3, said 45 bolts being also engaged in the vertical slot

4 formed in the clamping plate 5. Thus it will be seen that the beam 6 of the drill can be clamped between the bar and plate 5. The lower end of the bar 1 is partially twisted, as at 7, and has its lower end provided with a plate 8 which is arranged at right angles to the bar 1, said plate being provided with spaced longitudinal slots 9 and in which are engaged bolts 10, said bolts being adapted to be moved toward or 50 away from each other and being capable of being held in their adjusted positions by the clamping nuts 11 and 12, the latter nuts serving as jamb nuts.

Rotatably mounted on the bolts 10 are 60 rollers 13 which are adapted to receive the forward peripheries of the drill disks 14 therebetween. Thus it will be seen that the drills will be positively held in converging 65 relation.

What is claimed is:—

1. In combination with a double disk drill, an attachment comprising a bar adjustably connected to the beam of the drill frame, said bar having a plate carried by 70 its lower end, bolts adjustably mounted on the plates, and rollers carried by the bolts for engaging the drill disks.

2. In combination with a double disk drill, an attachment comprising a vertical 75 bar adjustably connected to the beam of the drill frame, said bar having its lower end terminating in a plate disposed at right angles to the bar, said plate having slots formed therein, bolts adjustably mounted 80 in the slots and having rollers carried thereby and engaging the drill disks therebetween, as and for the purpose set forth.

In testimony whereof I affix my signature, in the presence of two witnesses.

AUGUST F. LIPPERT.

Witnesses:

RUSSELL D. CHASE,
H. B. SPANTON.
